UNITED STATES PATENT OFFICE.

ABRAHAM TROSKY, OF NEW YORK, N. Y.

DESIGN FOR A BELT.

Application filed May 1, 1926. Serial No. 17,534. Term of patent 3½ years.

To all whom it may concern:

Be it known that I, ABRAHAM TROSKY, a citizen of the United States of America, and a resident of the city of New York, borough of Manhattan, in the county and State of New York, have invented a new, original, and ornamental Design for a Belt, of which the following is a specification.

Reference is to be had to the accompanying drawing in which the figure is a face view of a belt showing my new design.

I claim—

The ornamental design for a belt as shown.

ABRAHAM TROSKY.
